F. P. RUDDER.
STEAM GENERATOR.
APPLICATION FILED JUNE 1, 1912.

1,102,959.

Patented July 7, 1914

UNITED STATES PATENT OFFICE.

FRANK PERY RUDDER, OF DERBY, ENGLAND, ASSIGNOR TO GEORGE FLETCHER AND COMPANY LIMITED, OF LITCHURCH, DERBY, ENGLAND.

STEAM-GENERATOR.

1,102,959.

Specification of Letters Patent.

Patented July 7, 1914.

Application filed June 1, 1912. Serial No. 700,966.

To all whom it may concern:

Be it known that I, FRANK PERY RUDDER, a British subject, residing at Derby, county of Derby, England, have invented certain new and useful Improvements in Steam-Generators, of which the following is a specification:

This invention relates to steam generators more particularly adapted for use in cane sugar factories where large reserves of steam are required and the situations of which generally present exceptional transport difficulties. In such factories, the fuel is principally the refuse fiber from the cane, containing a high percentage of moisture, and generally of a character that necessitates its being gasified and burnt in a furnace at some distance from the boiler; the products of combustion being led from a combustion chamber and passed over the heating surface of the boiler—the transfer of heat to the water being almost entirely by means of conduction. Therefore it will be readily appreciated that the type of steam generator most suitable to these conditions, will be one wherein the gases are divided and broken up into many streams of flow, and distributed evenly over the heating surface, coupled with rapid circulation of the water. Several of the well known types of water tube boilers on the market, embody fully, such advantages, but it is generally admitted that their thermal reserve, *i. e.*, their water and steam carrying capacity is very limited, and such a reserve is of the utmost importance in a sugar factory where the quality of the fuel varies from hour to hour and even the supply may be checked for short periods—and where also sudden extra steam demands may occur, due to the intermittent working of large boiling pans.

Formerly the horizontal cylindrical multi-tubular boiler was universally used in the sugar factories, but while such boilers provide satisfactory thermal reserve they have many disadvantages.

(a). The circulation of the water is comparatively poor under all conditions. If fired direct through the tubes as they really should be, to obtain the best transfer of heat to the water, and also to avoid severe local strains on the shells, the tubes soon become choked with the fine and light ash, carried in suspension with the gases from the fiber fuel; and also the ends of the tubes are

burnt away at the firing end of the boiler. If fired under the shell, the efficiency is relatively poor, and the shell is subjected to serious local strains which almost always result in grooving at the seams nearest the combustion chamber, especially where efficient furnaces and consequent high temperatures are present.

(b). Large units (for which there is a natural demand with large factories) for high working pressures (which is also now universally specified), become very heavy and difficult of transport. In fact, with this type of boiler the heating surface of single units is practically limited to from 2500 to 3000 square feet, whereas units having twice this amount of surface are regularly desirable.

For these and other reasons, the water tube type of boiler has been used in many factories of recent years, but with these the insufficiency of thermal reserve has at once been felt, and to compensate for this it is often necessary to carry, and have under steam, more boiler power than is actually required, to avoid serious pressure fluctuations in ordinary working. This is a disadvantage of considerable importance, as then not only are the capital charges increased, but the active heating surface generally is being used inefficiently. Steam generators have also been proposed in which a screen of water tubes forming part of the main circulating system are placed between the furnace and the fire tubes of boiler.

My invention consists essentially of a composite steam generator comprising an external furnace, a fire tube boiler and a water tube boiler the tubes of which latter are interposed between the furnace and the fire tubes so as to form a screen, the water tube boiler being a separate unit with water and steam drums forming an independent circulation and being also connected by pipes to the fire tube boiler. A superheater may also be placed between the water tube boiler and the fire tube boiler.

The invention will be fully described with reference to the accompanying drawing which shows a longitudinal section of the steam generator. The composite steam generator is made in two sections a water tube section A and a tubular shell section B. The tubes *a* of the water tube section form a screen for the tubular shell which receives

the gases after they have passed over the said tubes *a*. The water tube section comprises a steam drum *C* and a water drum *D* connected by the afore-mentioned water tubes *a*, which latter are arranged in inclined or upright position, an independent circulation taking place through these tubes. The tubular shell section comprises a unit of a tubular generator *B* of ordinary construction without a fire box or grate. The water tubes *a* take up the highest heat from the gases and protect the shell of the tubular generator *B* from the action of the very hottest gases. The tubular unit *B* is connected with the drums *C* and *D* by water circulating tubes *c* and *d* and with the steam space of the drum *C* by a steam pipe *c'* the steam being preferably drawn off from the unit *B* by the steam pipe *b*.

20 Baffle plates *E* of metal or refractory material are placed behind the lower portion of the water tube screen to direct the flow of gases upward so as to traverse the water tubes *a* and give up a considerable portion 25 of their heat thereto before passing to the fire tubes of the shell section *B*. A steam superheater *G* when employed is placed at or near the top of the water tube screen *A* between the drum *C* and the shell *B* so that 30 the gases impinge thereon before entering the fire tubes. The superheater tubes may be arranged as shown or in any other suitable manner. For large installations in order to reduce the weight and size for trans- 35 port two or more of the tubular shell sections *B* may be connected to a single water tube screen section *A*, or two or more drums *C* may be employed to be connected with one or more drums *D*.

40 With the composite boiler now suggested, the following advantages over existing types are obtained, viz:—

(a). A screen of water tube heating surface with rapid and positively directed cir- 45 culation, is provided to receive the heat from the hottest gases, which are split up into many streams so that a very effective trans- 50 fer of heat results and the temperature of the gases is reduced to a moderate tempera- 55 ture before being passed to the tubular shell section of the boiler. In passing through the screen any ash carried in suspension is separated from the gases and deposited in the ash pit or in ash pockets provided for 60 the purpose.

(b). An improved lengthwise circulation will be set up in the shell section due to the rush of water that will take place from the drum *C* of the water tube section to the 65 shell section, through the circulating tubes *c*.

(c). A steam and water reserve almost double that of any type of water tube boiler is obtained.

(d). Large installations for the highest 70 pressures may be arranged, without any dif-

ficulty of transport arising from great weight of any part. In the largest installation the shell sections or units *B* need not be more than 6 ft. diameter by 16 ft. long, and therefore, the use of very heavy plates 70 for shells and ends would be avoided.

(e). The water tube heating surface section may be added to existing cylindrical boilers, thus forming them into larger and more efficient installations at relatively small 75 cost.

What I claim as my invention and desire to protect by Letters Patent is:—

1. In a steam generator, the combination with a furnace having a flue leading from the combustion chamber thereof, of a fire tube boiler unit having its tubes connected to receive the heated gases from said flue, a water tube boiler unit interposed between the fire tube boiler unit and said combustion 80 chamber, the tubes of the water tube boiler unit extending transversely across said flue, and means for causing the heated gases in the flue to flow along the tubes of the water tube boiler unit and thence transversely between such tubes and for protecting the shell of the fire tube boiler unit.

2. In a steam generator, the combination with a furnace having a flue leading from the combustion chamber thereof, of a fire tube boiler unit having its tubes communicating with said flue, an upright water tube boiler unit interposed between the fire tube boiler unit and said combustion chamber and having its tubes extending transversely 90 across said flue, water circulating connections between the lower and upper portions of the water tube boiler unit and the fire tube boiler unit, and means for dir. 95 the gases along the tubes of the water tube boiler unit and thence transversely between said tubes and into the tubes of the fire tube boiler unit and for protecting the shell of the latter unit.

3. In a steam generator, the combination with a furnace having a flue leading from the combustion chamber thereof, of a fire tube boiler unit having its tubes communicating with said flue, an upright water tube boiler unit interposed between the fire tube boiler unit and said combustion chamber and having its tubes extending transversely 110 across said flue, the water tube boiler unit having upper and lower water circulating drums, water circulating connections be- 115 tween the upper and lower drums of the water tube boiler unit and the water space of the fire tube boiler, a steam connection between the upper drum and the steam space of the fire tube boiler unit, and a steam outlet pipe leading from the fire tube boiler unit.

4. A steam generator comprising in its construction three separate units: an external furnace, a water tube unit with inde- 120

pendent circulation, upon the tubes of which the hot gases first impinge, and a fire tube unit placed beyond the water tube unit, circulating pipes connecting the water space and the steam space thereof, and a steam superheater placed between the water tube unit and the fire tube unit.

In testimony whereof I have hereunto set my hand in presence of two subscribing witnesses this 18th day of May 1912.

FRANK PERCY RUDDER.
